KEY CASE

Filed Jan. 22, 1931

UNITED STATES PATENT OFFICE

SEBASTIAN SCHMALZGRUBER, OF BLOOMFIELD, CONNECTICUT

KEY CASE

Application filed January 22, 1931. Serial No. 510,518.

My present invention has for its object to provide a key case of a simple, inexpensive nature in which the construction is such that the key hangers may be placed closer together or farther apart at the will of the user, thereby to allow for different size and thickness of keys without interfering with proper placement thereof in a compact mass when the holder case is closed and secured together.

Further, it is an object to provide a case in which the hangers are mounted by means of a coil spring held in a rigid support and itself supported at intervals throughout its length against mis-alignment, the coil spring being of sufficient strength to retain the heads of the hangers against accidental detachment while at the same time permitting them to freely swivel and be swung about the axis of the spring and also to permit them to be disconnected from the spring when it is desired to change their location along the spring.

Further, it is an object of the invention to so form the heads of the holders that they will not become entangled with the coils of the spring and also enable the holders to be made wholly of wire in one piece each if desired.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing, in which:

Figure 1 is a plan of a case embodying the invention.

Figure 2 is an enlarged cross section thereof.

Figure 3 is an elevation of the hanger portion shown in Figure 2 taken from the opposite side.

Figure 4 is an elevation of the hanger portion shown in Figure 2 taken at right angles to that figure.

Figure 5 is a detail perspective view of a portion of the invention.

Figure 6 is a detail perspective view of one of the hangers.

Figure 7 is a plan of the blank of the mounting plate.

Figure 8 is a similar view of a modified form of such blank.

Figure 9 is a section similar to Figure 2 showing the modified form of mounting plate in position on the cover 4.

In the drawing in which like numerals of reference indicate like parts in all of the figures, 1 represents the mounting plate which is provided along one edge with a series of projections 2 bent into the form of eyes for the reception of the coil spring 8, the spring being held against longitudinal movement out of the mounting plate by means of lugs 3 bent over at right angles after the spring has been inserted.

The mounting plate 1 is secured to a leather or other flexible back 4 by suitable rivets 6 or otherwise, the back 4 being foldable and having its folded parts adapted to be held together by snap fasteners 5 in the usual way.

It will be observed that the eyes 2 are spaced apart a greater distance than the width of the eyes in order to expose considerable lengths of the spring 8 so that one or more hangers may be connected to the spring between each pair of eyes 2 and at varying distances from said eyes as may be found desirable. The spaces between the eyes 2 are indicated by 7 in the drawing.

In order to keep down the expense of manufacture I prefer to make the hangers each of a single piece of wire and when so made they comprise the shank 9, the head 12, the loop 10 and a suitable portion 11 to engage the shank 9 to close the loop and prevent keys from accidentally becoming disconnected from the loop.

When made of wire it is essential that the head 12 be so constructed as not to catch or interlock with the coils of the spring 8 and to this end I form the head 12 by coiling the wire as at 13 and 14 and filing off the end 15 and projecting it slightly into the eye of the head so that there will be no points to

catch on the coils of the spring 8. The loop portions 13 and 14 are mashed tightly together as shown in Figure 4, thereby is produced a knob-like head having a wedge-like portion at 15, see Figure 4 that will fit the interior diameter of the spring and be of sufficient thickness not to accidentally pull out between adjacent coils of the spring, and yet be of such construction that by exerting a sufficient force the head 12 may be pushed out between adjacent coils of the spring and inserted between other coils if desired so that the hangers, which are located adjacent the eyes 2, may be spaced farther apart or closer together as may be found desirable, in order to enable keys of various thickness and sizes to be compactly placed together without forming undue humps in the case when closed, an objection that is now so common in other cases of similar type.

10 In Figures 8 and 9 those parts corresponding to similar parts in the preceding figures bear the same numbers of reference plus the index letter *z*.

15 From the foregoing description, taken in connection with the accompanying drawing, it is thought the complete construction, operation and advantages of my invention will be clear to those skilled in the art to which it relates.

20 What I claim is:

1. In a key case, a rigid supporting plate having spaced coil spring retaining loops, a coil spring located in said loops with portions thereof of substantial length located between the loops and exposed, and a set of key hangers having heads removably and swivelly and swingably located in said exposed coil portions, said hangers being pend-
35 ent from said coil spring, said hangers comprising wires having at one end key loops and at the other end head loops coiled closely together and having a wedge-shaped portion for entering the spring in the insertion and
40 removal of the hanger.
2. In a key case, a rigid supporting plate having spaced coil spring retaining loops, the spaces between the loops being of greater length than the width of the loops, a coil
45 spring located within said loops with substantial portions exposed between the loops, and a set of key hangers each of which comprises a rod-like body having one end coiled through approximately 500° to constitute a head, the
50 coiled end of the wire being bevelled and mashed flat against the remainder of the coiled portion to provide a wedge-shaped entering part of the wire for introduction between and removal from the coils of the
55 spring, substantially as specified.
